BOTTLE

Harold Brandeis, Milwaukee, Wis., assignor to Poly Plastic Bottle Co., Inc., Milwaukee, Wis., a corporation of Wisconsin

Filed Nov. 7, 1960, Ser. No. 62,744

Term of patent 14 years

(Cl. D58—6.5)

Fig. 1.

Fig. 2.

Fig. 3.

Fig. 4.

Fig. 5.

The dominant features of my design reside in those portions thereof illustrated in full lines.

I claim:
The ornamental design for a bottle, as shown and described.
